UNITED STATES PATENT OFFICE

ALBERT OLGAY, OF GLEN ELLYN, ILLINOIS, ASSIGNOR TO GAW-O'HARA ENVELOPE COMPANY, OF CHICAGO, ILLINOIS, A CORPORATION OF ILLINOIS

ENVELOPE MACHINE

Application filed March 3, 1926. Serial No. 91,905.

This invention pertains to the manufacture of envelopes of the two-in-one or duplex character, such for instance as that shown in the patent to Sawdon #1,470,291 of October 9, 1923, and is more particularly directed to a machine adapted, among other uses, to their manufacture.

The manufacture of duplex envelopes involves a number of operations and with the slow and inaccurate hand methods in vogue before the present machine was devised, entailed an expense wholly out of proportion to the profits. Following the usual mode of procedure, the two blanks, termed herein major and minor or auxiliary blanks, after being cut to the proper shape and size, and after the major blank had been provided with a window and a slit to receive the auxiliary blank, were suitably gummed, and then assembled by hand. The operator applied gum about the margin of the window opening in the major blank, that is, on the surface which would be interior when the envelope was folded, and applied a previously cut patch of substantially transparent paper over the opening and against the gum; thereafter the same or a second operator applied gum approximately to certain predetermined portions of the interior face of the major blank adjacent and below the ends of the slit, applied gum along a line approximately parallel and adjacent the edge of the flap of the auxiliary blank, ran his or her fingers through the slit to open it, inserted the edge of the flap of the auxiliary envelope blank through the opened slit with the gummed line of the auxiliary blank toward the lip of the slit farthest from the aforementioned gummed portions of the major blank and thereafter engaged the gummed portion of the auxiliary blank with the adjacent lip of the major blank and the gummed portions of the major blank with the body ends of the auxiliary blank. The assembled and secured

blanks were then stacked and fed to a folding machine or folded by hand.

The machine to be described herein has been designed to receive the cut, windowed and slit major blanks and the cut auxiliary blanks, and to perform all of the manual manipulations mentioned above, including the folding, if required. One such machine has been built and operated with a production of as high as one hundred and twenty assemblies per minute, which would compare with the production of from ten to twenty skilled operators making duplex envelopes by hand.

One of the primary objects of my invention may therefore be said to reside in the provision of a machine adapted to gum predetermined portions of continuous or substantially continuous streams of major and auxiliary envelope blanks, to apply a window patch over the window openings of the major blanks, to assemble each of the major or auxiliary blanks with one of the other blanks and to fold the major blanks about their assembled auxiliary blanks to provide duplex envelopes.

Another important object lies in the provision of a machine adapted to perform any one or any combination of the several operations hereinbefore set forth; for instance, a machine adapted to merely apply gum to predetermined portions of sheets of material, or to merely apply patches over perforations in sheets of blank material and the like, or again, to apply gum about the margins of the window openings of windowed envelope blanks, and a window patch over the opening and to thereafter fold the envelope blank to form a closure.

Another object includes the provision of a unique type of window patch applying mechanism adaptable for independent use as above noted. In this connection I have also devised a novel arrangement whereby the window patches, usually cut from "glassine",

a transparent paper, may be cut in a desired size and as needed by the applying mechanism. This mechanism is described and claimed in my copending application Serial No. 177,490, filed March 23, 1927.

5 A further object includes the provision of a mechanism adapted to insert successive sheets of material or other articles within openings or slits provided in other successive sheets or articles.

10 A still further object is to provide an easy and novel method by which one sheet of gummed material may be inserted through a slit formed in another gummed sheet of material or other article, whether the inserting be done by machine or by hand.

15 Many other novelties including the provision of a mechanism to prevent parts of the gumming mechanism from contacting with their cooperative parts should blanks fail to be fed to, or become jammed before reaching the gumming mechanism, in combination with the several features noted above and the provision of numerous devices of an advantageous nature including the details of their construction, should be quickly appreciated from the description and claims and from the drawing, in which:

20 Fig. 1 is a top plan view of a machine constructed in accordance with the invention.

Fig. 2 is a side elevation of the machine shown in Fig. 1 viewing the machine of Fig. 1 from the right looking lengthwise of the sheet.

Fig. 15 is a vertical section of the patch applying mechanism taken on the line 15—15 of Fig. 17.

Fig. 16 is a detail view of the operating mechanism for the patch applying mechanism 70 looking at the right hand end of Fig. 17 viewing the sheet in the direction of its length.

Fig. 17 is a top plan view of the patch applying mechanism and operating means therefor, parts being broken away.

75 Fig. 18 is a plan view of a portion of the rear end of my machine coupled to the forward end of a folding mechanism adapted to fold the duplex envelopes.

Fig. 19 is a vertical section taken on the line 19—19 of Fig. 18.

Fig. 20 is a diagrammatic illustration of the manner in which the major and minor and auxiliary envelopes are prepared and combined.

85 Fig. 21 is a view of a duplex envelope ready for folding and

Fig. 22 is a perspective view, taken from the front, of a duplex envelope after being folded and ready for use. For further views 90 of this envelope see the Sawdon patent to which reference has above been made.

The machine in general

Generally speaking the machine may be 95 said to consist of a major blank operating mechanism including a conveyor, an auxiliary blank operating mechanism, mechanism for combining the auxiliary blanks with the major blanks and means for pressing and 100 folding the assembled or combined blanks. The larger blank operating mechanism and conveyor may be said to include a magazine for supplying the blanks, a feed mechanism for delivering the blanks from the magazine 105 onto the conveyor, a conveyor adapted to receive the blanks fed to it from the feed wheels and carrying pins for timing the forward feed of the blanks with the conveyor, gumming mechanism for applying gum to certain predetermined portions of the blanks carried by the conveyor, mechanism for dropping a cooperative gumming roll or platen 110 out of cooperative position with the gumming roll should envelopes or blanks for any reason cease to pass between the gumming rolls, means for cutting window patches and 115 applying them over the window openings in the major blanks, mechanism for opening a preformed slit in each major blank, mechanism for inserting an auxiliary blank in the slit of each major blank, a secondary conveyor, mechanism for momentarily arresting the travel of the major blank during the auxiliary blank inserting operation, a pressing 120 device for pressing the assembled blanks together to secure their gummed portions and mechanism adapted to automatically receive the combined blanks and fold them successively into duplex envelopes. The auxiliary 125

130

blank mechanism also includes a magazine, a conveyor, a feed mechanism adapted to feed the blanks from the magazine onto the conveyor, means in connection with the conveyor for predetermining or timing movement of the blanks with the conveyor, an envelope flap scorer or creaser mechanism adapted to turn the flap of each auxiliary blank, mechanism for applying gum along a predetermined line adjacent the flap of each auxiliary blank, a secondary conveyor with means for turning and tilting each auxiliary blank into a position where it may be inserted within the opened slit in its corresponding major blank, mechanism for temporarily retarding or holding one corner of each auxiliary blank to permit a diagonally opposite corner to swing into position for insertion in the slit of its corresponding major blank and mechanism for completely inserting each auxiliary within the open slit of its corresponding major blank.

The machine generally is mounted upon a suitable frame 2 which is provided with brackets, bearing bosses, bearings etc. wherever needed and as such fall well within the skill to be expected of the ordinary mechanic they will be but generally described herein. The machine and the several mechanisms forming part of it are for the most part driven in synchronism and from any suitable source or sources of power, although in the present instance I prefer to utilize a single electric motor 3, geared down through a gear 4 and a pulley 6 to drive the main power shaft 7 through the intermediary of a belt 8. The power shaft 7 is provided with an idling pulley 9 and a splined pulley 10 in order that the belt 8 may drive the machine or not, as desired, by shifting the belt with the belt shifter 11, while the opposite end of the shaft is equipped with a hand wheel 12 in order that the machine may be operated by hand if at any time such be desirable.

Referring to Figs. 1, 2, 4, 5 and 6, it will be noted that the belt shifter 11 is arranged to be operated by means of a lever 13 if the operator is at the front or magazine end of the machine and by means of several levers 13' which are connected to a rock arm 14 running down one side of the machine and suitably supported therealong and connected to a lever 15, a pivoted link 15' and connection 16 to the shift bar 11 if the operator is out of reach of the lever 13. One lever 13' is shown arranged on the side of the machine opposite that along which the rock arm 14 is supported but is connected across the machine to the rock arm, as shown in Figs. 1, 4 and 6. This mechanism is also well within the skill of the ordinary mechanician to construct and for this reason further description is deemed unnecessary.

From the shaft 7 power is delivered to the various mechanisms as will more clearly appear hereinafter, but it should be understood that if it be desired to drive the several mech-

anisms independently or dependently upon one another through several different sources of power or power transmitting mechanisms, this may be readily arranged. I do not, therefore, desire to be limited to the use of a single countershaft or of a single electric motor or other power device.

The major blank magazine, feed, conveyor and operating mechanism

The front or forward end of the machine carries brackets 17 upon which a plate 18 carrying bearing brackets 19 is mounted and in the bearing brackets 19, which also support part of the auxiliary blank feed and drive mechanisms, a magazine 20 is pivotally mounted, as shown at 21, in order that the magazine, which is adapted to receive a stack of uniformly aligned major blanks (designated A in Figs. 5 and 20) may be adjusted to various angles to suit the angle at which the feed wheel 22 will contact or is to contact with the blanks. Bars 23 pivoted to the magazine at 24 (one on each side) are arranged for adjustment in clamp blocks 26 which are pivoted on a rod 27 forming a portion of the frame 2 of the machine. By unclamping the bars 23 they may be slid through the blocks 26 to any desired position and secured, as will be understood, to vary the inclination of the magazine. Each side of the magazine 20 is provided with a guide strip 28 which is adjustable toward and from its opposed guide strip by means of clamps 29 engaged in slots 31 formed transversely of the magazine. In this manner the magazine may be accommodated to various sizes of major blanks.

The feed wheel 22 is mounted on a shaft 33 driven by means of a sprocket 34 and chain 35 from a sprocket 30 keyed to the power shaft 7. The construction and operation of the feed wheel are old and well known and do not form, except in combination, a portion of the invention hereof, although for a thorough understanding of a feeding mechanism suitable for my present purpose reference is made to my prior Patent No. 1,443,430, dated January 30, 1923 and assigned to the assignee of the present application. It will suffice for my purposes here to say that the feed wheel is preferably driven in timed relation to the conveyor mechanism and supplies the blanks from the magazine 20 one at a time but in close succession.

The conveyor mechanism for the major blank may be best understood by reference to Figs. 1, 5, 6, 7 and 8, wherein it will be observed that angle guideways 36 are arranged longitudinally of the machine and on either side of the magazine; and in order to maintain their vertical sides in alignment with the guide strips 28 whether the latter be toward or from one another, these angle guide-ways are suitably supported by forked projections 37 attached to their bottoms and

engaged over bars 38 extending transversely of the machine (only one forked member 37 being shown in Figs. 5 and 10, for the sake of clearness). When it is desired to adjust these guide-ways to new positions thumb screws 39 (see Fig. 10) are loosened and the guides shifted toward or from one another, as the need may be, along the transverse bars 38. At intervals lengthwise of the machine 5 transverse bars 41 are arranged to serve as supports for a number of hold-down or presser guides 42 for the blanks, and also extend longitudinally of the machine and preferably from some point to the rear of the 10 feed wheel, two preferably cooperating with the angle guides 36 to hold the edges of the blanks down in proper position and those in the center serving to keep the paper from warping or bulging as it passes along the 15 conveyor. These guides also are supported by forked members 43 secured to the bars 41 by thumb screws 44 in order that they may be adjusted transversely of the machine to any desired position. 20 Cooperatively engaging the feed wheel 22 for feeding the major blanks onto the conveyor is a wheel 45 which is secured on a shaft 46 carried in brackets 46' in turn pivotally carried by a bar 46" forming a 25 transverse member of the machine. Through the medium of adjusting screws 47 and set screws 47' the cooperative feed wheel is adjusted with respect to the feed wheel 22. Sprockets 47" carrying the conveyor chains 30 35 48 are also mounted for transverse adjustment on the shaft 46 which is driven by a gear 49 meshing with a gear 51 secured on the shaft on which the feed wheel is mounted. The conveyor chains 48 pass over sprockets 40 52 splined for transverse adjustment along the shaft 53 and over transversely adjustable idlers 54 which are supported by depending brackets 55 secured to the bearing bosses of sprockets 52, while channel guides 56 45 50 55 60 65 70 75 80 85 90 95 100 105 110 115 120 125 130 135 140 145 150 155 160 165 170 175 180 185 190 195 200 205 210 215 220 225 230 dow opening O and the pads or dies 75 and 77 being formed and arranged to apply gum as indicated at G'. The gumming roll 74 is driven through the intermediary of a sprocket 78 secured to the shaft 73 and over which chain 35 is arranged, while gum is supplied to the dies or pads 75, 76 and 77 by a positively driven roll 79 mounted on a shaft 80 and geared through a gear 81 meshing with a gear 82 secured to the shaft 83.

10 The shafts 80 and 83 are journalled in the side members of a receptacle 85 and the shaft 83 carries a gum supply roll 84 revolving in the receptacle 85 which is filled with glue. The receptacle is supported by the transverse frame members or transverse bars 41. The gum roll 84 is positively driven and for this purpose the shaft 83 is extended to the side of the frame 2, journalled therein as shown at 86 and connected through a gear 87 with a gear 88 secured to the shaft 73 carrying gumming roll 74. It will here be noted that the feed, conveyor and gumming roll are driven in timed relation one with the other.

15 The gumming roll 74, in order to properly perform its function of gumming each major blank as it passes along the conveyor, is provided with a cooperative platen roll 89 mounted on a shaft 91 to provide a support for the blanks as they are gummed, but as it would occasion series trouble were the gumming roll to contact with the surface of the platen which might happen should blanks fail to be fed for any reason, I provide suitable mechanism such as that described and claimed in my application Serial No. 14,658, entitled Machines for manufacturing book covers and the like, filed March 11, 1925 and assigned to the assignee of the present application, or similar mechanism, such as that now to be described to prevent such possibility.

Platen drop mechanism

45 In the present instance the gumming roll 74 is prevented from contacting with the face of the platen roll 89 which is preferably rubber covered, by dropping the platen below the line of contact or tangency between the gumming dies 75, 76 and 77 and the surface of the platen. The platen roll 89, as has been stated before, is mounted on a shaft 91 to which a gear 92, adapted to mesh at all times with gear 88, is secured and is carried 50 in bearings formed in the ends of arms 93 pivoted at their opposite ends on stub shafts 94 secured to brackets 95 attached to the frame 2 of the machine. The platen roll, its shaft and the gear 92 may swing about the pivots or trunnions 94 to a slight extent when lock bars 96 (one on each side of the machine) are swung in an anti-clockwise direction (viewing Fig. 3) about their pivots 97 and thereby released from engagement 55 with ends of bars 98 secured to the arms 93.

Normally, that is, when major blanks are being fed successively and in their desired order through the machine along the conveyor they ride over the tops of rods 99, which are preferably placed between the conveyor chains 48, holding them down in the positions indicated in Figs. 3 and 8. As these rods are rigidly secured to adjustable link bars 101, (one on each side of the machine) which also serve as a weight and as 70 both the rods 99 and link bars 101 are pivoted on a transverse bar 102 extending across the machine and the rods in their lowermost positions lie against the tops of the adjacent frame member 38, the rods and link bars are 75 held against counterclockwise rotation.

The adjustable link bars 101 are in turn connected by rods 103 pivoted to the bars 96 and consequently should the machine for any reason fail to feed the major blanks continuously along the conveyor, the rods 99 will be swung in a clockwise direction (viewing Fig. 3) about the pivots 102 under the influence of the weight of the adjustable links 101 and thereby release the lock bars 96, which 80 for their purpose are provided with a shoulder, from engagement with the bars 98 and the platen roll will drop until limited by the platen returning mechanism.

85 The platen return mechanism includes vertically movable arms 104 (one on each side of the machine) pivotally secured at 105 to the bearings formed in the ends of arms 93 for reception of the shaft 91, and provided with longitudinal slots 106 through which 90 the shaft 73 of the gumming rolls extends. A cam follower 107 is pivotally secured to the upper end of each arm 104 and is adapted to follow the movements of a cam 108 fixedly secured to the shaft 73 to rotate as the shaft 105 and gumming roll rotate.

95 When the major blanks are passing through the machine properly the platen roll is held in its uppermost position and cooperates with the gumming roll and in this position the high point 109 of the cam 108 is arranged to just clear the cam follower 107, but when the platen roll has dropped because of failure of feed of the major blanks the cam follower being attached to the arm 104 110 drops with the arm and the roll and, because of the slot 106, engages at all times throughout the surface of the cam 108. As the high point 109 of the cam lies between the same 115 radii and in the subtended arc of the gumming dies or pads 75, 76 and 77, the dies or pads will be disposed diametrically away from the platen when the high point of the cam cooperates with the cam follower 107 to raise the arm 104 and thus the platen roll 120 to their normal positions upon each revolution of the gumming roll. If at the time the platen roll has been lifted to its normal operative position the blank feed has recontinued, the blanks will force the rods 99 about 125 130

their pivots 102 and thereby return the lock bars 96 to their position of support beneath the bars 98.

It will be clear thus far that the major blanks are fed onto the conveyor chains and carried thereby in predetermined timed relation to the gumming roll where gum is applied about the window opening for attachment of the window strip or patch and to predetermined portions of the blank adjacent the ends of the slit for the purpose of securing auxiliary envelope blanks when desired. From the gumming roll the blanks pass, still carried by the conveyor chains, to mechanism for applying a window patch over the window opening of each and for opening the slit for the insertion of the flap of the auxiliary envelope.

Patch applying mechanism

Beyond the gumming roll and parallel to the axis thereof, a shaft 111 is mounted in bearings 112 and 113 suitably supported upon the frame of the machine and on this shaft, which is driven through a gear 114 meshing with an idling gear 115 in turn driven by the gear 88, a creasing roll 116 and a patch applying device generally designated 117 are fixedly secured. Referring more particularly to Figs. 5, 9, 10, and 15 to 17, inclusive, it will be observed that the patch applying mechanism includes two parallel spaced discs 118 and 119 through which a shaft 121 is journaled and between which a gripper finger 122 is secured to the shaft 121. A block 123 is secured between the discs 118 and 119 by means of screws 124 which pass into the discs and serve as an abutment between which and the gripper finger 122, the "glassine" or other window strip or patch material is held during a portion of the window laying or applying operation. This block, together with the faces of the discs, which for the purpose are adjustable toward and from one another, also serves to prevent the window patch or strip from falling between the discs while the discs are being rotated to laying position.

The shaft 111 is, of course, driven in synchronism with the gumming conveyor and feed mechanisms and arranged so that when the window patch or strip has been carried to a position substantially diametrically opposite that in which it is received, the gripping finger 122 will be released to drop the strip or patch in proper position over the window of the blank passing therebeneath. The gripper finger 122 is also arranged to remain in released position until it assumes a position just prior to that illustrated in Fig. 15 when the window strip will be fed into position for gripping by the end 126 of the gripper. The shaft 121 is also journaled in a disc 127 which is secured to shaft 111, has a collar 128 secured to it and is surrounded

by a coiled spring 129 secured at one end to the collar 128 and at its opposite end to an abutment 131 on disc 127; the spring tending at all times to rotate the shaft 121 and thus the gripper finger 122 in a counter-clockwise direction, viewing Fig. 16, or in a clockwise direction, viewing Fig. 15.

The outer end of the shaft 121 is equipped with a pinion 132 which meshes at all times with a sector gear 133 pivoted at 134 to the disc 127. The sector gear 133 is provided with a cam follower 135 rotatably secured on a pivot pin 136 and adapted to roll around the face of a cam 137 loosely arranged on the shaft 111 but held in a stationary position by a bolt 138 from the frame engaging a lug 139 thereon. The creasing roll 116, as will be noted from Figs. 8, 10 and 17, is formed in two halves and adapted to be clamped about the shaft 111 by means of bolts 141 and is also provided with an arcuate slot 142 for passage of the end of shaft 121 freely therethrough in order that either the roll 116 or the patch applying mechanism or both may be adjusted axially and radially of the shaft 111.

The cam 137 is so shaped that upon rotation of the shaft 111 in a clockwise direction (viewing Fig. 16) the sector gear will be rotated in an anti-clockwise direction about its pivot 134 when the cam follower 135 strikes the cam shoulder 143 thereby rotating the shaft 121 through the pinion 132 in a clockwise direction against the tension of spring 129 to open the jaws of the gripper; i. e., swing the gripper finger 122 away from the block 123. The shaft 111 continues to rotate and because of the shape of the cam 137 the gripper finger remains in its open position until the cam shoulder 144 is reached at which time the gripper finger has reached a position just prior to that shown in Fig. 17 and where mechanism to be hereinafter described inserts a window strip or patch between the gripper end 126 and the plate 123. At this instant or immediately thereafter the cam follower 135 is urged down the shoulder 144 to the lowermost surface of the cam under the torsional action of spring 129, which through its connections to shaft 121 rotates it and causes the gripper finger 122 to securely clamp the window strip or patch between it and the block 123. In this position the window patch is carried to a position substantially diametrically opposite that in which it was received where, upon re-engagement of the cam follower 135 with the shoulder 143, the gripper finger 122 is opened and the window patch deposited or laid. Because of the timed relation of the window patch or strip mechanism with the conveyor and other parts as before noted, the patch is deposited in a predetermined position on, or in other words directly over, the window opening in the major blank.

The creasing roll 116 is designed with an

arcuate shoulder 115' cooperative with the edge of a roll 116' to crease the lip L of each blank A along a line L' to turn the lip upwardly from the plane of the paper, (viewing Fig. 20) while provision is made in a similar manner for support of the patch applying discs in aid of the patch applying operation. For this purpose a shaft 111' is journalled in the side members of the frame of the machine (see Fig. 9), and driven through a gear 114' meshing with the gear 114 secured on the shaft 111 and on the shaft 111' discs 118' and 119' are secured for adjustment longitudinally of the shaft to correspond with any adjustments of the patch applying mechanism. The disc 116' is also adjustably secured on the shaft 111' so that it may be moved circumferentially of the shaft or axially thereof, as may be desired.

20 *The patch supplying and cutting mechanism*

The patch supplying and cutting mechanism is generally indicated in Figs. 1, 2 and 4, but is shown on a larger scale in Figs. 10 and 11. Suitably mounted on the frame of the machine are standards 145 which carry an undercut guide block 146 on which a carriage 147 is mounted for adjustment transversely of the machine to correspond with adjustments of the patch applying mechanism, as will be understood. A set screw 148 serves to lock the carriage to the guideway in adjusted position and also serves to secure a pair of guides 149 concentric with the discs 118 and 119. These guide-ways 149 are preferably of L-shape in cross section, as will be noted, and guide the window patch or strip during its passage from its point of reception to its point of release preventing it from becoming crumpled or from working out of alignment. Securely mounted on the carriage 147 are a pair of standards 151 bearing between them an idling roll 152, positively driven feed rolls 153 and 154, a revolving knife holder 155 and a stationary shearing blade 156. The standards 151 are each provided with an arm 157 between which a shaft 158 carrying a brushing disc 159 of rubber and a pulley 161 is revolvably mounted, while secured to one standard as shown at 162 is an adjustable arm 163 carrying a spindle 164 upon which a roll 165 of window patch or strip material is revolvably mounted. Any suitable spring mechanism 165' or other friction device may be arranged on the spindle 164 to retard rotation of the roll of window strip paper to prevent it from over-feeding, as will be obvious.

The shaft 166 upon which the feed roll 153 is mounted also carries a pulley 167 over which and the pulley 161 a belt 168 is trained and reversed in order to drive the brushing disc 159 in a clockwise direction (viewing Fig. 11); the feed roll 153 being driven in an anti-clockwise direction by shaft 166 in

turn driven by chain 169 trained over a sprocket 170 on shaft 111. The pulley 167 is splined to the shaft 166 in order that it may be adjusted longitudinally thereof whenever the carriage 147 is adjusted and a gear (not shown) secured on shaft 166 between the pulley 167 and the adjacent standard 151, meshes with a gear 171 to drive the feed roll 154, and the gear 171 meshes with the idling gear 172 to drive the gear 173 attached to the knife roll 155 in the same direction as the feed roll 154, i. e., anti-clockwise, viewing Figs. 4 and 11.

Between the standards and over their tops a bar 174 is mounted and arranged to secure 80 guide fingers or wires 175 which are of the shape substantially of that shown in Fig. 10, within grooves 176 formed in the feed roll 154 to substantially the same depth as the diameter of the wire. It will be noted that 85 the lower ends of the guide fingers or wires 175 extend tangentially from the bottom of the feed roll 154 and as the window strip material is fed between these feed rolls these ends prevent the severed end of the ribbon of 90 window strip material, as will clearly appear hereinafter, from following the upper roll. The lower feed roll 153 is likewise grooved at two or more points as at 177 to receive round leather belts 178 which at 95 their opposite ends are trained over small pulleys 179 secured on a shaft 181 mounted between two arms 182 secured to the carriage 147 in any desirable manner, while idling pulleys 183 serve to guide the lower side of the 100 belts over the edge of the carriage.

The stationary shearing blade 156 is adjustably mounted fore and aft of the standards in grooves 184 and cooperates with a spring pressed blade 185 resiliently carried 105 in the knife roll 155. In order to resiliently support the blade 185 the roll 155 is bored out, as shown at 186, at several places between its ends on a line along the surface of the knife roll at an angle to a projection of the 110 axis of the roll along its surface and in these recesses 186 spring pressed plungers 187, adapted to be secured to the rear edge of the blade 185 and about each of which a spring 188 is coiled, are secured between the inner 115 end of the recess and plugs 189 threaded into the tapped mouth of each recess. The plungers 187 are slidingly received through the plugs 189 and are each provided with a nut and lock nut 191 for adjustment of the blade. 120 The knife roll at this portion is cut away and countersunk, as will be seen from Fig. 11, while the opposite side is recessed for the length and width of the blade 185 and along a line, at the surface of the roll, at an angle to a projection of the axis of the roll and parallel in space to the line of centers of the 125 borings 186, in order that it may slide therethrough without wobbling.

A roll of window material 165 is mounted 130

on the spindle 164 and the end of the ribbon 192 is threaded through the feed mechanism beneath the roll 152, between the feed rolls 153 and 154, between the knife roll 155 and 5 the stationary shearing blade 156, and to the brushing disc 159 over the tops of belts 178. Upon operation of this window cutting mechanism the ribbon 192 is fed forwardly to the proper length between the knife blades 10 and beneath the rubber brushing discs 159 which together with the belts 178 tends to urge it toward the gripper mechanism. When the proper length of ribbon has been thus carried forward the rotary knife blade 155 cooperating with the stationary blade 156 shears the ribbon and the foremost sheared-off end passes to the gripper finger 122 where it is grasped and later applied over the window on the major blank. As 15 the window strip or patch cutter mechanism is driven from the patch applying mechanism it will at once be clear that the two operate in synchronism or in timed relation. It will also be apparent that, depending upon 20 the ratio of gearing between the gripper mechanism and knife roll 155, various lengths of window strips or patches may be cut and if desired any one of the gears 171, 172 or 25 173 may be changed to vary the length of 30 window patch or strip.

Secondary conveyor and arresting mechanism for major blank

After the blank has had the lip L turned 35 up and the window patch applied it is carried on to a secondary conveyor on which it is held substantially stationary for a predetermined time during which the auxiliary blank is inserted through the open slit and positioned 40 properly wth respect to the major blank. For these purposes the frame of the machine is provided with a horizontal table 193 and with extended side frame members 194 between which pulleys 195 and 196 are journaled while belt tightener pulleys 197, four 45 in number, and carried by arms 198 pivoted on a shaft 199 mounted in the frame members of the machine serve by their own weight to keep belts 201, which are trained over pulleys 50 195 and 196, taut at all times. One or more angle guides 200 (one shown in Figs. 9 and 10) may be seated on the table 193 in order to guide the edges of the blanks as they pass therealong and at suitable intervals trans- 55 versely of the machine gravity drop idling rolls 202 are mounted on a transverse bar or rod 41 to hold the blanks down after they pass the patch applying and creasing discs and until the blanks are received on the conveyor 60 belts 201 and guided beneath rollers 203 adjustably secured at suitable points indicated at 204 (see Fig. 9) along suitable suspended longitudinal rods 205. The secondary conveyor belts are positively driven 65 by the pulley 195 which for this purpose is

connected by a chain 206 and suitable sprockets to shaft 111' and therefore blanks carried by the secondary conveyor belts 201 move in timed relation to the previously described mechanisms which have operated upon it.

During the inserting operations, that is, during the time when the auxiliary blank is being connected to the major blank it is preferable to hold the major blank substantially stationary. To arrest the motion of the major blanks a shaft 207, carrying adjustable blocks 208 each of which in turn is provided with a pin 209, is journaled in the extensions 194 of the frame of the machine adjacent the end of the table 193. A slotted rock arm 211 is secured to one end of the shaft 207, and connected to a push rod 212 through a pin 213 adapted to ride in the slot of the rock arm 211. The push rod 212 is pivotally connected at 214 to a bell crank lever 215 intermediately pivoted at 216 to the frame of the machine and supplied with a cam follower 217 at its other end. The cam follower 217 engages a cam 218 secured on the shaft 111' and following the contour serves to rock the bell crank lever 215 about the pivot 216 to alternately depress the pins 209 from a position where they would engage the edge of the blank and arrest its forward motion. Normally a tension spring 219 serves to keep the pins 209 in a vertical position to engage the edge of the blank and for this purpose is secured to the bell crank lever 215 adjacent the pivot 214 and to the frame of the machine at some convenient point. The cam 218 is arranged on the shaft 111' in such a manner as to time the arresting movement of the pins 209 in accordance with the time of supply of an auxiliary blank, as will more clearly appear hereafter. After the major and auxiliary blanks have been combined the arresting mechanism releases and permits the secondary conveyor to carry them beneath a presser roll 221 which rolls against the pulley 196 to thoroughly press the portions of the two envelope blanks together at their gummed portions in order that the envelope blanks will not be creased by the pressing action of the presser roll 221 operating against the belts 201. The pulley 196 is preferably 11 grooved to receive the belts 201 so that the top surface of the belts will fall flush with the surface of the roll.

The blank folding mechanism.

In Figs. 1 to 5 inclusive and Fig. 9 I have shown a third conveyor mechanism for carrying the assembled blanks to some point for subsequent operation, but in Figs. 18 and 19 I have shown an arrangement which is at the present time preferred whereby the assembled blanks after being pressed are delivered into the feed end of a folding machine, such as that described and claimed in Patent #1,179,573, April 18, 1916, although for my purposes I 130

have slightly modified the construction in a manner which will be fully explained herein-after.

Referring first to the construction shown in Figs. 1 to 5 and 9 it will be noted that the extension members 194 carry vertical members 222 in which the presser roll 221 is journaled and at the outer ends depending portions 223 serve to support and journal a shaft 224 carrying a pulley roll 225 which is geared through a worm gear 226 to a worm pinion 227 carried on a stub shaft 228 on which is also secured a sprocket 229 over which a chain 231 engages. The chain 231 is also engaged over a sprocket 232 carried on a shaft 232' carrying a large gear 233. Through this train of gearing and through other gearing to be described, by which the gear 233 is driven, the pulley 225 is driven slowly to drive a belt 234 trained thereover in a like manner, in order that the assembled envelopes may be closely packed on the top of the belt as they are fed thereto from between the presser 221 and the pulley 196 from the secondary conveyor, or, where an operator may pick them up in bulk and dispose of them as desired.

But referring to Figs. 18 and 19 in which the preferred combination of my machine is shown, the assembled blanks after being pressed are fed directly onto conveyor chains 235 and engaged by pins 236 secured to the chains whereby they are carried along with the chains in a predetermined timed relation to the subsequent folding mechanisms. As in the initial conveyor mechanism for the major blanks this conveyor is provided with angle guides 237 one on each side and which may be adjusted toward and from one another, with suitable top guides or presser bars 238 supported from cross members 239, and with a bottom support or guide 241 against which a leaf spring 242 is adapted to press, being adjustably arranged on one transverse cross member 239 by a clamp 243, to frictionally retard the assembled blanks until the pins 236 of the conveyor chains pick them up. Certain of the guide or presser bars 238 project upwardly at an incline at their forward ends, as shown at 24', for the purpose of guiding the assembled blanks properly into the conveyor mechanism.

The conveyor chains 235 are positively driven by any suitable mechanism and here for that purpose I have illustrated a drive shaft 245 which may be connected in any suitable manner to the source of power 3, and to the shaft 245 a bevelled gear 246 meshing with a second bevelled gear 247 on a stub shaft 248, is secured. A sprocket (not shown) is also secured on the stub shaft 248 and on a shaft 249 sprockets 250 are secured for driving the conveyor chains 236. Arms 251 (but one shown) are suitably secured to the frame of this conveyor mechanism which is supported on suitable legs 252, and carry idling

sprockets 253 which serve to keep the comparatively long length of each conveyor chain taut. This conveyor mechanism serves to time the assembled blanks with respect to the folding mechanism which is not shown since a clear understanding thereof may be had by reference to the patent mentioned above.

The auxiliary blank mechanism auxiliary blank feed

The magazine 254 is adjustably mounted on brackets 255 mounted on uprights 256 and since this magazine, its construction and arrangement, are substantially similar to the magazine 20 a specific description is deemed unnecessary. The feed mechanism including the feed wheel 257 and a cooperative presser wheel 258 are mounted in suitable brackets 259, secured to the frame members of the machine, to each other by proper cross members and to a transverse bar 260 supported on opposite sides of the frame of the machine above the line or level of travel of the major blanks, but are otherwise so similar to the feed mechanism of the major blanks that their further description except for the manner of drive is also deemed unnecessary here. An inspection of the drawing will confirm this statement.

The feed wheel 257 is secured to a shaft 261, one end of which is provided with a sprocket 262 over which passes a chain 263 also engaged with a sprocket 264 secured on the shaft 33 of the major blank feed wheel 32. The shaft 261 at its other end is provided with a gear 265 adapted to mesh with a gear 266 secured on the shaft 267 on which the cooperative auxiliary blank feed roll 258 is secured. It will thus be apparent that the feed mechanism for the major and auxiliary blanks are driven in timed relation or synchronism.

Conveyor mechanism and drive

Referring more particularly to Figs. 1, 8 and 12, it will be noted that the shaft 266 carrying the cooperative feed wheel 258 also carries a pair of sprockets 268 (one only shown) which engage chains 269 carrying pins 271 and in other ways similarly arranged to conveyor chains 48 of the major blank conveyor mechanism. These chains 269 are trained over suitable sprockets 270 secured on the shaft 272 spaced down the conveyor-way a suitable distance beyond a roll for creasing the flap F of each auxiliary blank, as will more clearly hereinafter appear. As the auxiliary blanks are fed onto the conveyor chains by the feed mechanism the friction retarding device 68, the function of which has been previously described and which is mounted on a transverse supporting bar 273, retards the forward motion of each blank until its rear edge is picked up by the

pins 271 and thereby carried forwardly and downwardly on the conveyor.

Suitable guide bars 274 secured to transversely adjustable blocks 275 mounted on a transverse frame connecting member 276 extend longitudinally of the auxiliary blank conveyor and are similar to the hold-down guides 42 and to the bars 244 in arrangement and function. Intermediate the conveyor chains 269 is a strip 277 which serves to support the center portions of the bottoms of the auxiliary blanks, but this strip 277 terminates adjacent the shaft 272, and L-shaped guide-ways 278, one adjacent each conveyor chain 269, serve to guide the auxiliary blanks in their travel in the same manner that the L-shaped guide-ways 36 guide the major blanks.

20 *Flap turning or creasing mechanism*

The insertions of the flap F of the auxiliary blank through the open slit S of the major blank is facilitated by creasing the flap F along the line C and this also results in spacing the edge E of the auxiliary blank away from the outside face of the major blank when the two are assembled, as noted in Fig. 22, so that this flap may be readily grasped by the fingers for bending down and securing to the outside face of the major blank for sealing the auxiliary envelope. The flap F is also previously gummed along its marginal edge E on that surface opposite the one shown in Fig. 20 prior to placement in the magazine 26 so that it may be secured to the outside face of the major blank for sealing the auxiliary envelope formed therewith. The outside face of the major blank is also to be considered as that face which is opposite the one shown in Fig. 20.

Mounted between the brackets or auxiliary frame members 259 and journaled therein are two shafts, a lower shaft 279 and an upper shaft 281 on the ends of which meshed gears 282 and 283 are respectively secured for the purpose of driving the two shafts together. The chain 263 which drives the feed mechanism passes over a sprocket 284 secured on the shaft 279 in order to drive these two shafts 279 and 281, which will be termed creasing roll shafts, in synchronism with the feed and conveyor. Also mounted on the shafts 279 and 281 are the cooperative creaser rolls 285 and 286 respectively, the lower creasing roll 285 carrying a circumferential rib 287 fitting into a groove 288 provided in the upper roll 286 so that when the auxiliary blanks pass there-between the flap will be creased along the dotted line C, as shown in Fig. 20. Both rolls are so arranged on their respective shafts that they may be adjusted transversely of the machine or axially of the shafts to accommodate various sizes of auxiliary blanks and the bearings of the shaft 281 of the upper roll are preferably

adjustable by means of set screws 289 to permit the creasing rolls to be engaged with the requisite pressure.

25 *Auxiliary blank gumming mechanism*

Succeeding the flap creasing rolls is the gumming mechanism which includes a gumming roll, generally designated 291, carried by shaft 292 on which sprockets 293 and 294 are secured over the first of which the chain 263 passes in order to drive the gumming roll in synchronism with the feed, the conveyor and the creasing rolls, and over the second of which a chain 295 is arranged for driving engagement with the sprocket 296 secured on a shaft 297 for driving the gum supplying device as will later appear. The gumming roll 291 is preferably formed in two halves, as will be noted from Figs. 12 and 13, in order that it may be adjusted axially of the shaft 292 on which it is mounted and secured thereon in an adjusted position. One-half of the gumming roll 291 is provided with an edge 298 of greater radius than the radius of the complementary half and along this edge 298 gum is supplied. The arcuate length of the edge 298 depends on the length of the line or portion of the auxiliary blank along which it is desired to apply the gum, as for instance at G" in Fig. 20. As the auxiliary blank 29 passes beneath the gumming roll 291, the latter is so timed with respect to the travel of the blank that it will apply the gum along the proper line and within the proper limits of the blank and aiding this purpose a co-operative gumming roll 299 idly supported on a stub shaft 301 secured on an arm 302 at its other end adjustably mounted on a transverse bracket connected to rod 303, serves to press the blank upwardly into engagement with the edge 298 or to support the blank while it is being gummed.

A standard 304 similar to the standards 145 supports a gumming receptacle 305 between the side walls of which shafts 297 and 307 are journaled. On these two shafts gum supply rolls 308 and 309 are respectively journaled, the first for the purpose of dipping into the liquid gum contained in the receptacle and the second for the purpose of receiving its gum from the first and applying it to the edge 298 of the gumming roll 291, while an adjustable wiper mechanism including a wiper finger 311 and an adjustable wing screw 312 mounted through a transverse bar 306 connected across the standard serves to remove surplus gum carried upwardly by the roll 308. The shaft 297 also carries a gear 313 which meshes with a gear 314 on the shaft 307 in order that both gumming rolls 308 and 309 may be positively driven.

Chain tightening idlers and arms, as indicated at 315, 316, 317 and 318, are mounted on suitable portions of the frame of the machine to tension the chains 263, 169 and 295 respectively.

tively and others may be provided wherever it may be necessary or desirable to have them.

The secondary conveyor for the auxiliary blanks

5 After the auxiliary blanks have had their flaps creased and have been gummed as before described it is necessary that they be conveyed over and adjacent the major blanks as they 10 are passed along to the secondary conveyor of the major blank for assembly. This requires that the auxiliary blanks, which in this machine have been to this point carried along in a path above but substantially parallel to 15 the path of the major blanks, be turned at an angle and carried down to a point where they may be inserted in the major blanks.

The first turning movement of the auxiliary blank is accomplished by means of spring 20 belts 319 trained at one end over pulleys 321 secured on the pulley shaft 272 and at the other end over a roll 322, the first of a series of 25 rolls 323, all of which are positively driven and for the purpose rotatably supported in parallel guide-ways 324 and 325 which are 30 suitably supported upon the frame of the machine and inclined inwardly and downwardly toward the secondary conveyor of the major blank. The belts 319 are preferably of 35 spring material in order to compensate for movements of the shaft 292 when adjusted which for this purpose is provided with any suitable adjusting means, such as that generally designated 326.

35 The rolls 322 and 323 are journaled in the guide-ways 324 and 325 so that the guide-ways will project upwardly above their top surfaces as clearly indicated in Fig. 10, in order that the auxiliary blanks in their travel 40 downward will not jump the track. Above the roller way and supported from suitable transverse members of the frame of the machine are strips 327 from which depend idling 45 rolls 327' which also aid in preventing the blanks from jumping the track during their travel. For the purpose of driving the rolls 323 and certain truncated rolls 328, 329 and 330, a counter-shaft 331 carrying bevelled gears 332 which mesh with bevelled gears 333 carried on the ends of the roller axles, 50 is suitably journaled in a frame member 334 attached to the guide-way 324. This counter-shaft 331 is driven through the medium of a bevelled gear 335 secured on the end 55 of a stub-shaft 336, which is in turn driven by a chain 337 passing over a sprocket 338 secured thereon. The chain 337 at its other end passes over a sprocket (not shown) secured 60 on a second stub-shaft 339 suitably journaled in the frame of the machine and this stub shaft is in turn driven by a gear 341 meshing with a gear 342 secured on the shaft carrying pulley 195. Since this shaft carrying pulley 195 is driven through the medium of suitable sprockets and chain 206 from shaft 111'

it follows that not only is the pulley 195 driven in a counterclockwise direction, viewing Figs. 2 and 3, but that the rolls 323, 328, 329 and 330 will also be driven in the same direction viewing the same figures and that 70 the large gear 233 through its engagement with gear 342 will be driven in a clockwise direction to drive the pulley roll 225 in a counter-clockwise direction.

When the auxiliary blanks reach the spring 75 belts 319 they are turned slightly at an angle to the direction in which they were formerly traveling and guided onto the inclined secondary conveyor along which they are urged by the positively driven rolls 322, 323, 328, 329 and 330 until they are received by the inserting mechanism to be described. During the passage of these auxiliary blanks down the secondary conveyor over the rolls 322 etc. presser rolls 327' carried by the strips 80 327 prevent the auxiliary blank from jumping the track or from warping or bulging.

In order to properly insert the lowermost corner of the flap F within the open slit S of the major blank the auxiliary blank is tilted to drop this corner of the flap which is indicated at X below the adjacent corner of the blank indicated at Y. This is accomplished by providing the tapered and truncated rolls 328, 329 and 330, but it is also necessary to 90 swing the auxiliary blank slightly about the corner P to facilitate its insertion and to accomplish this, I provide a releasable blank pivoting and hold-down mechanism, as will 95 now appear.

Hold-down roll and release mechanism

Suitably mounted transversely of the machine is a supporting bar 343 which supports the guide-ways 324 and 325 by means of 105 brackets 344 and on this transverse supporting bar or rod a bell crank lever, generally designated 344', having arms 345 and 346 is pivotally mounted for rocking movement. The arm 345 of this bell crank lever adjustably supports a yoke 347 in the arms of which a hold-down roll 348, adapted to roll against the roll 330 is journaled. The arm 346 of the bell crank lever is pivotally connected to a reciprocal rod 349 at its opposite end pivotally connected to a yoke or forked member 350 which engages over shaft 111' for reciprocal motion under the influence of a cam follower 351 which engages a cam 352 carried by the shaft 111'. The rod 349 and member 350 are retracted or moved by a spring 353 secured to it and to the frame at 354, (see Fig. 2).

The auxiliary blanks as they pass down their secondary conveyor along the rolls 323 pass beneath the hold-down roll 348 and preferably just as the rear corner P passes between the rolls 330 and 348 and immediately after the cam 352 operates to reciprocate the rod 349 to raise the roll 348 out of en- 125 130

gagement with the rear corner of the blank, the inserting mechanism comes into operation.

The inserting mechanism

- 5 The inserting mechanism comprises, a channel shaped member 355 secured to a lug 356 suitably pivoted at 357 to the frame of the machine, a bar 358, the length of which is 10 adjustable by means of thumb screws 359, pivoted at 360 to the channel member 355, a bell crank lever, generally designated 361 pivoted at 362 to the frame of the machine with one arm 363 slotted as at 364 to engage 15 a pin 365 connected to the bar 358 to provide a lost motion connection therewith, and a push rod 366 pivotally connected at 367 with the other arm 368 of the bell crank lever 361 and pivotally connected at its other end at 20 369 to a horizontal arm 370 secured to the end of the yoke member 350 adjacent the point of connection of the rod 349. The spring 353 not only serves to retract the rod 349 but also to retract the rod 366 and the inserting mechanism.
- 25 When the machine is in operation, rotation of the shaft 111' drives the cam 352 which is so timed with the travel of the auxiliary blanks that, when the rear corner P of the auxiliary blank has come between the hold-down roll 348 and the truncated roll 330, it will force the cam follower 351 away from the shaft 111' and through the rod 349 and the bell crank lever 344', raise the roll 348 to 30 release the blank; but at this instant, although immediately after the roll 348 has been raised because of the lost motion connection 364, 365, the inserting mechanism is operated through the same cam to engage the bottom edge Z of the auxiliary blank, a corner of the flap of which has just prior thereto entered the slit S in the major blank approximately as shown in Fig. 20, swinging or pivoting the auxiliary blank about the point 35 where it engages the end of the slit in the major blank until the whole of the flap F of the auxiliary blank has been passed through the slit to the desired position, for instance, as is shown in Fig. 21.
- 40 In some instances, particularly when the paper of the envelope material is thin and limp, I use guide and support wires 372, 373 and 374, which are suitably supported in any desirable manner. The wire 372 aids in holding the major blank down on its conveyor, while the wires 373 and 374 serve to prevent the auxiliary blanks from buckling or warping when the inserting mechanism is operating.

The operation

When it is desired to operate the machine to perform the various operations on the major and auxiliary blanks in order to manufacture duplex envelopes the previously cut

major blanks A, which have also been slotted and cut to provide the window openings, are placed in the magazine 20 which is, of course, adjusted to the proper width and elevated to the required heights and the auxiliary 70 blanks B which have been cut to the proper shape and size are placed in the magazine 254 likewise adjusted to receive them. The major blank, feeding, gumming, window applying and supplying mechanisms are also adjusted laterally of the machine in order that they may perform their several functions in the proper manners on the major blank and the auxiliary blank feeding, creasing rolls and gumming roll are also adjusted laterally of 75 the machine to perform their several functions of the auxiliary blank in the proper manner.

The major and auxiliary blank feed mechanisms and conveyors, the major blank arresting mechanism and the auxiliary blank inserting mechanism being driven in synchronism or timed relation with one another and with other portions of the machine, each major blank will be carried successively beneath the gumming mechanism and gumming roll 74 for application of gum to the points G and G', beneath the slit creasing and opening roll 116 and simultaneously beneath the discs 118 and 119 for application of the window patch, and then to the arresting mechanism where it is momentarily held by the pins 209, while one of the auxiliary blanks is being carried between the creasing or flap turning rolls 285 and 286 beneath the gumming roll 291 for application of gum to the line G'' down the inclined conveyor provided by the spring belts 319 and rollers 323, 328, 329 and 330, and has its flap F inserted within the slit in the major blank, first partially, by reason 90 of the fact that the corner of the flap X is tilted downwardly, with respect to its normal plane of travel as well as with respect to the body of the auxiliary blank, so that it readily 95 slides through the upturned lip L of the slit S, and second completely, by reason of the movement of the channel shaped inserting member 355 engaging the rear edge Z to 100 swing the auxiliary blank into proper alignment with the major blank and its slit.

105 It will be noted, that during the inserting of the auxiliary blank through the slit in the major blank the body portion of the auxiliary blank is held above the gummed portions G' while it is being inserted and until recession 110 of the inserting member 355 when the body portion is permitted to drop down into contact with the gummed portions G' of the major blank. It will also be noted that at one side of the slit S two spots or places have 115 gum applied to them but that at the other side namely, at that side adjacent the corner at the end of the slit where the flap of the auxiliary blank is first entered but one spot or 120 place has gum applied to it and that spot or 125

place is at substantially the most remote possible place for engagement with the body of the auxiliary blank. The arrangement of the gummed portions and holding the body of the auxiliary blank above the body of the major blank during the inserting operation permits the auxiliary blank to be swung about the corner where the flap abuts the end of the slit (see Fig. 20) to insert the whole of the flap beneath the upturned lip L of the major blank without touching or smearing the glue at G' at undesirable points of either the major or auxiliary blank. The lip L is preferably raised to such point that it will clear the gummed line G'' during the inserting operation.

After the inserting member 355 has re-ceded and an auxiliary blank has had its flap inserted through the slit of a major blank the auxiliary blank settles down against the gummed portion G', the arresting mechanism releases, that is, the pins 209 are dropped below the conveyor belts 201 and the assembled blanks pass beneath the presser roll 221 which closes the lip L of the major blank against the gummed portion G'' of the auxiliary blank, and presses the body of the auxiliary blank and the window patch against the gummed portions G' and G respectively, from whence the assembly passes on to the conveyor 234 to any desired point, or preferably on to the conveyor chains 235 of the folding machine which is fully described in the patent aforesaid.

It will be appreciated that the auxiliary blank mechanism may be disconnected or permitted to operate idly and the major blank mechanism operated solely for the purpose of applying window patches to slotted or unslotted blanks; or if desired the major blank mechanism may be operated idly and the auxiliary blank mechanism operated to perform any one or all of the operations except inserting. If desired also two or more window cutting, supplying and applying mechanisms may be incorporated for the simultaneous or successive application of two or more window patches to two or more individual adjacent, staggered or successive window openings formed in blanks passing through the major blank mechanism. For some purposes this is desirable since some window envelopes are made double and later cut in half. Perforating mechanism for perforating either the major or minor blanks if desired may be incorporated in the machine or substituted for any of the several mechanisms operating on the respective blanks and numerable other uses and adaptations of my invention will be readily appreciated.

While I have described and illustrated a machine which I have built and operated successfully and which is at the present time a preferred embodiment of the invention, it should be understood that many changes of

details and operation may be resorted to without departing from the spirit of the invention and the scope of the appended claims.

I claim:

1. A machine for making double envelopes comprising in combination, means for feeding major and minor envelope blanks in substantially parallel paths for a part of their travel to a predetermined position, and means at said position for combining said blanks to form a double envelope. 70

2. In combination, means for separately feeding a major envelope blank having a slit therein and a minor envelope blank having an edge adapted to be passed through the slit in said major blank, to a predetermined position, and means at said position for moving one blank relatively to the other to pass said edge through said slit. 80

3. A machine for making double envelopes comprising in combination, means for positioning a major envelope blank having a slit and means for automatically inserting an edge of a minor envelope blank in said slit. 85

4. A machine for making double envelopes comprising in combination, means for feeding slotted blanks in succession to a predetermined envelope position, means for supplying articles at said position, and means for passing a portion of an article through each slit. 90

5. A machine for making double envelopes comprising in combination, means for holding an envelope blank having a slit therein and means for moving a second blank bodily relative to the first said blank to insert an edge portion of the second said blank through the slit in the first. 100

6. In combination, means for feeding a major envelope blank having a slit therein, means for feeding a second envelope blank and means cooperative with both feed means for inserting a portion of said second envelope blank in said slit. 105

7. In combination, means for feeding a succession of major envelope blanks each having a slit therein, means for supplying a plurality of minor envelope blanks and means for inserting a minor blank in the slit of each major blank. 110

8. In combination, means for feeding a slit envelope blank, means for creasing an edge portion of a second envelope blank and means for inserting said edge portion through said slit. 120

9. In combination, means for feeding a slit envelope blank, means for gumming an edge portion of a second blank, and means for inserting said edge portion through the slit in the first said blank. 125

10. In combination, means for feeding a slit envelope blank, means for gumming a second blank along a line spaced from a marginal edge thereof, and means for inserting 130

- said edge inclusive of said gummed line through the slit in the first said blank.
11. In combination, means for feeding a slit envelope blank, means for gumming a second blank along a line spaced from a marginal edge thereof, means for entering a corner of said marginal edge in the slit in the first said blank and means for urging the balance of said edge inclusive of said gummed line through said slit.
12. In combination, means for feeding an envelope blank having a slit therein, means for slightly raising one edge of the blank along the slit, and means for inserting an edge portion of a second blank beneath said raised edge.
13. In combination, means for feeding an envelope blank having a slit therein to a plurality of predetermined positions in succession, means at one of said positions for slightly raising one edge of the blank along the slit, and means at another position for inserting an edge portion of a second blank beneath said raised edge.
14. In combination, means for feeding an envelope blank having a slit therein, means for raising one edge of the blank along the slit to provide a lip, means for creasing a marginal edge of a second blank to incline said edge with respect to the rest of the blank, and means for inserting said inclined edge through said slit in the first said blank.
15. In combination, means for feeding an envelope blank having a slit therein, means for raising one edge of the blank along the slit to provide a lip, means for applying gum along a predetermined portion of a second blank along a line adjacent and substantially parallel to a marginal edge thereof, means for creasing said marginal edge between the line of application of said gum and the edge to incline said edge with respect to the rest of the blank, and means for inserting said inclined edge through said slit in the first said blank inclusive of the gummed line.
16. In combination, means for feeding a plurality of major envelope blanks each having a slit, in predetermined timed relation, means for relatively moving the edges of the slit of each blank to provide an opening through the blank, and means for inserting a portion of a second envelope in the opened slit of each major blank.
17. In combination, means for feeding major envelope blanks each having a slit, in timed succession, means for opening the slit of each major blank, means for supplying a minor envelope blank for each major blank and means for passing a portion of a minor blank through the opened slit of each major blank.
18. In combination, conveyor mechanism means for feeding a slitted envelope blank and a second envelope blank onto said conveyor mechanism in predetermined relation,
- means for performing an operation on each blank, and means for relatively moving said envelope blanks bodily to pass an edge portion of one through the slit in the other.
19. In a machine, means for opening a preformed slit in a piece of material and means for inserting an article in said opened slit.
20. In a machine, means for opening a preformed slit in a sheet of material and means for inserting an edge portion of a second sheet of material in said opened slit.
21. In a machine, means for opening a slit in a sheet of material with one of the edges of the material at the slit inclined to the general plane of the material, and means for inserting a second sheet of material partially through the opened slit.
22. In a machine, means for opening a preformed slit in a sheet of material so that one of the edges of said sheet at the slit will be inclined to the general plane of the sheet, means for applying a gum to a second sheet of material along a predetermined line adjacent an edge thereof, and means for passing said second sheet edge through said opened slit to a point where the inclined edge of the first sheet may be contacted with the gummed portion of the second.
23. In combination, means for feeding slitted envelope blanks in predetermined succession to a predetermined position, means for feeding auxiliary envelopes individually to a predetermined position adjacent the predetermined position of the slitted envelopes, means for relatively timing said feed means, and means operative in timed relation to said feed means for transferring successive auxiliary blanks from their predetermined position to the predetermined position of successive slitted blanks.
24. In combination, a magazine for major envelope blanks, a magazine for auxiliary envelope blanks, means for conveying blanks in succession from each magazine to predetermined adjacent positions, means between said magazines and said positions for performing an operation on each blank, and means at said positions for combining successive major and auxiliary blanks.
25. In combination, a magazine for slitted envelope blanks, a magazine for auxiliary envelope blanks, means for applying gum to a predetermined portion of each slitted blank, means for opening the slit in each slitted blank, means for gumming a portion of each auxiliary blank, and means for inserting an edge of each auxiliary blank through the slit of each slitted blank with the gummed portion of the auxiliary blank toward a face of the slitted blank at a portion adjacent the slit therein.
26. In combination, a pair of conveyors, a magazine for slitted envelope blanks, a magazine for auxiliary envelope blanks,

- means for feeding slitted and auxiliary blanks to their respective conveyors in succession, means for opening the slit in each slitted blank, means for applying gum to a portion of each auxiliary envelope adjacent a marginal edge thereof and means for passing said marginal edge including said gummed portion of successive auxiliary blanks relatively through the opened slit of successive slitted blanks. 5
- 10 27. In combination, a conveyor for envelope blanks, means for successively feeding slitted blanks onto said conveyor, means for opening the slit in each slitted blank, means for positioning each blank, and means for inserting an edge portion of an auxiliary blank in the slit of each of the slitted blanks when said slitted blank is positioned. 15
- 20 28. In combination, a conveyor for envelope blanks, means for driving said conveyor, means for feeding a succession of slitted envelope blanks onto said conveyor, means operative while said blanks are carried by said conveyor for opening said slit and applying gum to predetermined portions of each blank, means for positioning the blanks thus operated upon, and means for inserting a portion of a second envelope through the opened slit of each slitted blank when the slitted blanks are positioned. 25
- 30 29. In combination, a conveyor for envelope blanks, means for driving said conveyor, means for feeding a succession of slitted envelope blanks onto said conveyor, means operative while said blanks are carried by said conveyor for opening the slit of each blank, means operative while said blanks are carried by said conveyor for applying gum to predetermined portions of each blank, means for positioning the blanks thus operated upon, means for applying gum to a predetermined portion of an auxiliary envelope blank, and means for inserting an edge of an auxiliary envelope through the open slits of the slitted blanks when the latter are positioned. 35
- 40 30. In combination, a conveyor for envelope blanks, means for driving said conveyor, means for feeding a succession of slitted envelope blanks onto said conveyor, means operative while said blanks are carried by said conveyor for opening the slit and for applying gum to predetermined portions of each blank, means for positioning the blanks thus operated upon, means for bending an edge portion of auxiliary envelope blanks, and means for inserting a bent edge portion of an auxiliary blank through the open slit of each slitted blank when the latter are positioned. 45
- 50 31. In combination, a conveyor for envelope blanks, means for driving said conveyor, means for feeding a succession of slitted envelope blanks onto said conveyor, means operative while said blanks are carried by said conveyor for opening the slit and for applying gum to predetermined portions of each blank, means for bending an edge portion of auxiliary envelope blanks, and means for inserting a bent edge portion of an auxiliary blank through the open slit of each slitted blank when the latter are positioned. 55
- 60 32. In combination, means for feeding major and minor envelope blanks to a predetermined position, means at said position for combining said blanks, and means for thereafter carrying said blanks to a folding mechanism for folding the major blanks about the minor blanks to form duplex envelopes. 70
33. In combination, means for separately feeding a major envelope blank having a slit therein and a minor envelope blank having an edge adapted to be passed through the slit in said major blank, to a predetermined position, means at said position for moving one blank relatively to the other to pass said edge through said slit, and means thereafter operative for carrying said blanks to a folding mechanism for folding the major blank about the minor blank to provide a duplex envelope. 75
34. In combination, means for positioning a major envelope blank having a slit, means for automatically inserting an edge of a minor envelope blank in said slit, and means for feeding said blanks to a folding mechanism for folding said major blank about said minor blank to provide a duplex envelope. 80
35. In combination, means for feeding a succession of marginal envelope blanks each having a slit therein means for supplying a plurality of minor envelope blanks, means for inserting a minor blank in the slit of each major blank, and means for feeding said blanks to a folding mechanism for folding each major blank about a portion of the inserted minor blank to provide a duplex envelope. 85
36. In combination, means for feeding a slitted envelope blank, means for gumming a second blank along a line spaced from a marginal edge thereof, means for inserting said edge inclusive of said gummed line through the slit in the first said blank, and means for feeding said blanks to a folding mechanism for folding the first said blank about the said second blank to form a duplex envelope with the said edge protruding exterior of the folded blank. 90
37. In combination, means for feeding a slit envelope blank, means for feeding a slit envelope blank, means for gumming a second blank along a line spaced from a marginal edge thereof, means for entering a corner of said marginal edge in the slit in the first said blank, means for urging the balance of said edge inclusive of said gummed line through 95
- 100

- said slit, and means for feeding said blanks to a folding mechanism for folding the first said blank about the uninserted portion of the second said blank to provide a duplex envelope.
- 5 38. In combination, means for feeding an envelope blank having a slit therein, means for raising one edge of the blank along the slit to provide a lip, means for creasing a marginal edge of a second blank to incline 10 said edge with respect to the rest of the blank, means for inserting said inclined edge through said slit in the first said blank, and means for feeding said blanks to a folding mechanism for folding the first said blank 15 about the uninserted portion of the second said blank to provide a duplex envelope.
39. In combination, means for feeding major envelope blanks each having a slit, in 20 timed succession, means for opening the slit of each major blank, means for supplying a minor envelope blank for each major blank, means for passing a portion of a minor blank through the open slit of each major blank, and means for feeding said blanks to a folding 25 mechanism for folding each major blank about the uninserted portion of its minor blank to provide duplex envelopes.
40. In combination, conveyor mechanism, means for feeding a slitted envelope blank 30 and a second envelope blank onto said conveyor mechanism in predetermined relation, means for performing an operation on each blank, means for relatively moving said envelope blanks to pass an edge portion of one 35 through the slit in the other, and means for feeding said blanks to a folding mechanism for folding one blank about the other to provide a duplex envelope.
41. In combination, a magazine for major 40 envelope blanks, a magazine for auxiliary envelope blanks, means for conveying blanks in succession from each magazine to predetermined adjacent positions, means between said magazines and said positions for performing 45 an operation on each blank, means at said positions for combining successive major and auxiliary blanks, and means for feeding said blanks to a folding mechanism for folding each major blank about its auxiliary blank 50 to provide a duplex envelope.
42. In combination a magazine for slitted envelope blanks, a magazine for auxiliary envelope blanks, means for applying gum to a predetermined portion of each slitted blank, 55 means for opening the slit in each slitted blank, means for gumming a portion of each auxiliary blank, means for inserting an edge of an auxiliary blank through the slit of each 60 slitted blank with the gummed portion of the auxiliary blank toward a face of the slitted blank at a portion adjacent the slit therein, and means for feeding said blanks to a folding mechanism for folding the edges of each 65 slitted blank about the uninserted portion of its auxiliary blank to provide a duplex envelope.
43. In combination, a traveling conveyor, means for feeding individual blanks having window openings to said conveyor in substantially continuous succession, means for gumming each blank about the margin of its window opening and for gumming the blank at a plurality of other places simultaneously, means for laying a window patch over each opening and means for applying a second envelope blank against certain of said other gummed places.
44. In combination, a conveyor for carrying envelope blanks edgewise, means for driving said conveyor, means for feeding windowed envelope blanks to said conveyor, means operative to apply gum to a portion of each blank about a window opening therein and to a plurality of predetermined portions other than about said window opening while the blank is carried by said conveyor, means for applying a window patch over each window opening and against said gummed portion while the blank is carried by said conveyor, and means for applying a blank over said window patch and to said other predetermined portions of each envelope blank.
45. In combination, a conveyor for carrying envelope blanks edgewise, means for driving said conveyor, means for feeding windowed envelope blanks to said conveyor in predetermined timed relation to the rate of travel of said conveyor, means operative to apply gum and to a plurality of predetermined portions of each blank including a portion of the margin of each window opening while the blank is on said conveyor, means for applying a window patch over each window opening and against the gummed margin of the window opening while the blank is carried by said conveyor, and means for applying an auxiliary envelope blank to certain of said plurality of predetermined gummed portions of each envelope blank.
46. In combination, means for supplying envelope blanks each having a window opening and a slit therein, in substantially continuous succession, means for applying a window patch over each window opening, and means for inserting the flap of an auxiliary envelope blank through the slit of each of the first said blanks.
47. In combination, means for supplying envelope blanks each having a window opening and a slit therein, in substantially continuous succession, means for applying gum about the opening of each blank, means for applying a window patch over each opening, and means for inserting the flap of an auxiliary envelope blank through the slit of each of the first said blanks.
48. In combination, a traveling conveyor, means for feeding individual envelope blanks each having a window opening and a slit

therein, to said conveyor in substantially continuous succession, means for laying a window patch over each opening, and means for inserting the flap of an auxiliary envelope blank through the slit of each of the first said blanks.

49. In combination, a traveling conveyor, means for feeding individual envelope blanks each having a window opening and a slit therein, to said conveyor in substantially continuous succession, means for gumming each blank about the margin of its window opening, means for laying a window patch over each opening, and means for inserting the flap of an auxiliary envelope blank through the slit of each of the first said blanks.

50. In combination, a traveling conveyor, means for feeding individual envelope blanks each having a window opening and a slit therein, to said conveyor in substantially continuous succession, means for gumming each blank about a portion of the margin of the window opening therein and at a plurality of other places simultaneously, means for laying a window patch over each opening, and means for inserting the flap of an auxiliary envelope blank through the slit of each of the first said blanks and against certain of said other gummed places of the first said blanks.

51. In combination, means for passing envelope blanks each having a window opening and a slit from one point to another, means for supplying blanks to said passing means in independent succession, means for applying a window patch over each opening, and means for inserting the flap of an auxiliary envelope blank through the slit of each of the first said blanks.

52. In combination, means for passing envelope blanks each having a window opening and a slit therein from one point to another, means for supplying blanks to said passing means in independent succession, means for gumming a predetermined portion of each blank, means for applying a window patch over each opening, means for opening the slit of each blank, and means for inserting the flap of an auxiliary envelope blank through the open slit of each of the first said blanks.

53. In combination, means for passing envelope blanks in independent succession from one place to another, means for supplying blanks each having a perforation and a slit therein to said passing means, means for applying a cover patch to each perforation during passage of the blank, and means for inserting the flap of an auxiliary envelope blank through the slit of each of the first said blanks.

54. In combination, means for passing envelope blanks in independent succession from one place to another, means for supplying perforated and slitted blanks to said passing means, means for applying a patch over each perforation and means for performing a series of operations on each of said blanks including

inserting the flap of an auxiliary envelope blank through a slit of each of the first said blanks during their passage.

55. In combination, means for passing envelope blanks in independent succession from one place to another, means for feeding perforated and slitted blanks to said passing means, means for performing a series of operations on each of said blanks during their passage including means for securing a patch over each perforation, and means for inserting the flap of an auxiliary envelope through the slit of each of the first said blanks.

56. In combination, means for passing envelope blanks in independent succession from one place to another, means for supplying envelope blanks to said passing means, means for applying gum to a predetermined portion of each blank during its passage, and means for connecting an auxiliary envelope blank to each of the first said blanks.

57. In combination, means for passing envelope blanks in independent succession from one place to another, means for supplying envelope blanks to said passing means, means for applying gum to a plurality of predetermined portions of each blank during its passage, means for applying a sheet of material to certain of said gummed portions, and means for connecting an auxiliary envelope to certain other of said gummed portions of each of the first said blanks.

58. In combination, a conveyor for envelope blanks, means for continuously driving said conveyor, means for continuously feeding windowed and slitted envelope blanks in succession to said conveyor, means operative to apply gum to a predetermined portion of each blank while it is carried by said conveyor, means for applying a window patch over each window blank while the windowed blank is carried by said conveyor, and means for inserting the flap of an auxiliary envelope through the slit of each of the first said blanks.

59. In combination, a conveyor for envelope blanks, means for driving said conveyor, means for feeding windowed envelope blanks to said conveyor, said blanks each having a slit adjacent its window, means operative to apply gum to a portion of each blank about the window opening therein while the blank is carried by said conveyor, means for applying a window patch over the window opening and against said gummed portion while the blank is carried by said conveyor, and means for inserting the flap of an auxiliary envelope through the slit of each of the first said blanks.

60. In combination, a conveyor for envelope blanks, means for driving said conveyor, means for feeding windowed and slitted envelope blanks to said conveyor, means operative to apply gum to a plurality of predetermined portions of each blank including a portion of the margin of each win-

dow opening while the blank is carried by said conveyor, means for applying a window patch over each window opening and against the gum about the margin of the window opening while the blank is carried by said conveyor, and means for inserting the flap of an auxiliary envelope through the slit of each of the first said blanks.

61. In combination, a conveyor for envelope blanks, means for driving said conveyor, means for feeding windowed and slitted envelope blanks to said conveyor in predetermined timed relation to the rate of travel of said conveyor, means operative to apply gum to a predetermined portion of each blank while the blank is on said conveyor, means for applying a patch over each window opening while the blank is on said conveyor, and means for inserting the flap of an auxiliary envelope through the slit of each of the first said blanks.

62. In combination, a conveyor for envelope blanks, means for driving said conveyor, means for feeding windowed and slitted envelope blanks to said conveyor in predetermined timed relation to the rate of travel of said conveyor, means operative to apply gum to a portion of each blank about a window opening therein while the blank is on said conveyor, means for applying a window patch over each window opening and against said gummed portion while the blank is carried by said conveyor, and means for inserting the flap of an auxiliary envelope through the slit of each of the first said blanks.

63. In combination, a conveyor for envelope blanks, means for driving said conveyor, means for feeding windowed and slitted envelope blanks to said conveyor in predetermined timed relation to the rate of travel of said conveyor, means operative to apply gum to a plurality of portions of each blank including a portion about a window opening therein while the blank is on said conveyor, means for applying a window patch over each window opening and over and against the gummed portion thereabout while the blank is carried by said conveyor, and means for inserting the flap of an auxiliary envelope through the slit of each of the first said blanks with the body of the auxiliary blank against certain of the other gummed portions of the first said blank.

64. In combination, means for supplying envelope blanks each having a window opening and a slit therein, in substantially continuous succession, means for applying a window patch over each window opening, means for inserting the flap of an auxiliary envelope blank through the slit of each of the first said blanks, and means for feeding said blanks to a folding mechanism for folding the first said blanks about the auxiliary blank to provide a duplex envelope.

65. In combination, means for supplying

envelope blanks each having a window opening and a slit therein, in substantially continuous succession, means for applying gum about the opening of each blank, means for applying a window patch over each opening, means for inserting the flap of an auxiliary envelope blank through the slit of each of the first said blanks, and means for feeding said blanks to a folding mechanism for folding the first said blanks about the auxiliary blank to provide a duplex envelope.

66. In combination, a traveling conveyor, means for feeding individual envelope blanks each having a window opening and a slit therein, to said conveyor in substantially continuous succession, means for laying a window patch over each opening, means for inserting the flap of an auxiliary envelope blank through the slit of each of the first said blanks, and means for feeding said blanks to a folding mechanism for folding the first said blank about the auxiliary blank to provide a duplex envelope.

67. In combination, a traveling conveyor, means for feeding individual envelope blanks each having a window opening and a slit therein, to said conveyor in substantially continuous succession, means for gumming each blank about the margin of its window opening, means for laying a window patch over each opening, means for inserting the flap of an auxiliary envelope blank through the slit of each of the first said blanks, and means for feeding said blanks to a folding mechanism for folding each first said blank about the inserted auxiliary blank to provide a duplex envelope.

68. In combination, a traveling conveyor, means for feeding individual envelope blanks each having a window opening and a slit therein, to said conveyor in substantially continuous succession, means for gumming each blank about a portion of the margin of the window opening therein and at a plurality of other places simultaneously, means for laying a window patch over each opening, means for inserting the flap of an auxiliary envelope blank through the slit of each of the first said blanks and against certain of said other gummed places of the first said blanks, and means for feeding said blanks to a folding mechanism for folding each of the first said blanks about its auxiliary blank to provide a duplex envelope.

69. The method of manufacturing a duplex envelope from a major blank having a slit and a minor blank having a flap adapted to pass through the said slit, comprising, tilting the blanks relatively and with the minor blank flap at an angle relative to the said slit, passing a corner of the flap through the slit and thereafter swinging the blanks relatively to complete the insertion of the flap through the slit.

70. In combination, means for passing en-

velope blanks each having a perforated window opening in independent succession from one place to another, means for supplying envelope blanks to said passing means, means for applying gum to a marginal portion of the window opening and to a predetermined portion of each blank adjacent the gummed marginal portion of the window opening during the passage of the blank, means for applying a window patch over said opening, and means for applying a sheet of different material to the predetermined gummed portion of each blank.

71. In combination, means for supporting an envelope blank having a slit, and means for connecting a second blank to the slit blank with an edge of the second blank in predetermined relation to the slit in the slit blank by bodily moving one of said blanks relative to the other.

72. In an envelope machine, means for creasing a portion of an envelope blank, means for applying gum to a portion of said blank adjacent the creased portion, and means for applying a second blank to said gummed portion.

73. In an envelope machine, means for feeding envelope blanks in succession from one place to another, means operative during movement of said blanks from place to place for creasing a portion of each blank, means for applying gum to a predetermined portion of each blank adjacent its creased portion, and means for applying a second blank to the gummed portion of each blank.

In witness of the foregoing I affix my signature.

ALBERT OLGAY.
